[57] CLAIM

The ornamental design for a diving mask with two windows, as shown and described.

DESCRIPTION

FIG. 1 is a front, side top perspective view of a diving mask with two windows showing our new design, the broken line showing of the strap is for illustrative purposes only and forms no part of the claimed design;

FIG. 2 is a right side view of the mask of FIG. 1, the left side being identical;

FIG. 3 is a front view of the mask of the invention;

FIG. 4 is a rear view thereof;

FIG. 5 is a top plan view of the mask of the invention; and, FIG. 6 is a bottom plan view thereof.
